UNITED STATES PATENT OFFICE

ARCHIE M. NIVEN, OF DETROIT, MICHIGAN, ASSIGNOR, BY MESNE ASSIGNMENTS, TO
CONTINENTAL AIRCRAFT ENGINE COMPANY, A CORPORATION OF DELAWARE

ROCKER BOX HOUSING

Application filed September 18, 1929. Serial No. 393,341.

This invention relates to internal combustion engines and more particularly to an improved rocker box housing therefor which is specially adapted to be secured to the cylinder of an air cooled radial aircraft engine, though I do not limit my invention exclusively for use with aircraft engines.

A separate housing for the valve mechanism which includes the rocker arm has many advantages over the solid type of rocker arm housing, which is most generally cast integrally with the cylinder. In an engine provided with a separate housing, access may be had more easily to the working parts of the valve operating mechanism housed therein, thereby facilitating the repair and adjustment of the working parts of said valve operating mechanism. With the present type of separate rocker box housings most generally used, ready access is not had to the mechanism housed therein because the separate rocker arm housings are bolted down to the cylinder casting with a large number of bolts, thus entailing considerable time and effort in removing the housing for the purpose of making the necessary adjustments or repair to the valve mechanism.

It is the object of my invention to provide an improved form of housing for the valve operating mechanism that may be readily and easily removed, when it is necessary to have access to the valve operating mechanism housed therein.

A further object of my invention is to provide an improved engine structure in which a separate rocker box housing may be very quickly and readily assembled in proper position with respect to the rocker arm.

A still further object of my invention is to provide an improved type of internal combustion engine of the character as set forth above, in which a separate rocker box housing may be positively and firmly located and secured in the proper position with respect to the rocker arm, but which may be readily removed with a minimum of time and effort.

For a more detailed understanding of my invention, reference may be had to the accompanying drawings which illustrate one

form which my invention may assume, and in which:

Figure 1 is a vertical sectional view through a portion of an internal combustion engine constructed in accordance with my invention;

Figure 2 is a vertical cross-sectional view taken substantially on the line 2—2 of Figure 1 and showing the rocker box housing and the means for fastening the same in place;

Figure 3 is a detailed sectional view of a modified form of fastening means for fastening down the housing;

Figure 4 is a detail in perspective of the housing as illustrated in Figures 1 and 2;

Figures 5, 6 and 7 are vertical sectional views of further modified forms of construction showing various types of supports to which the housing structure is adapted to be secured;

Figure 8 is a detail in perspective of the bridge structure as illustrated in Figure 5.

A standard type of an air cooled radial combustion engine is herein illustrated and includes a cylinder casting A in which a standard type of valve, having a valve stem B, is supported, a standard valve operating mechanism being incorporated therewith and including a pivoted rocker arm C, that is arranged to be actuated by a push rod D to open and close the valve.

With my improved construction, I preferably provide a valve operating mechanism that is located substantially beyond the outer limits of the cylinder casting and is enclosed within a separate housing structure secured to the cylinder casting. The cylinder casting A is provided with a pair of spaced rocker arm supports 10 and 11 for each rocker arm.

As the construction of the valve mechanism for operating the exhaust valves and intake valves of the engine are substantially identical in structure, it is merely necessary to describe and illustrate but one structure, the structure illustrated in the drawings being adapted for either the intake or exhaust valve operating mechanisms. These permanent supports 10 and 11 are preferably cast integrally with the cylinder, but obviously the

same may be formed of separate brackets bolted to the cylinder casting if so desired. These supports are arranged to support a rocker arm shaft 12, which pivotally supports the rocker arm C, said rocker arm being connected to the valve stem and push rod in the usual manner.

This invention relates more specifically to the housing structure for enclosing the valve operating mechanism including the rocker arm, said housing being adapted to be very readily fastened down and assembled to the cylinder casting, and accurately located with respect to the rocker arm housed therein. I 10 preferably provide a bridge 13 (Figure 2) that is secured to the upper end of the spaced rocker arm supports 10 and 11 by means of the screws 14, the said bridge arranged to span the rocker arm. The central portion of 15 the bridge 13 is provided with the internally threaded recess 15 for receiving the externally threaded stud portion 16 of a fastening device 17. The rocker arm housing is preferably constructed of sheet metal and comprises an inverted box-like shell provided with a bottom wall 17', side walls 18 and end walls 19. The bottom wall or base 17' is provided with a perforation 20 and the side walls are provided with the cut-away portions 21, said housing being arranged to be 20 assembled to the engine structure, the perforation 20 brought in registration with the threaded hole in the bridge 13, and the fastening device 17 then screwed down, the flanges 25 21' carried by said fastening devices being adapted to clamp the bottom wall 17' of the housing to the bridge structure. The cut-away portions 21 of the housing provide clearance for the head of the rocker arm shaft 40 and the nut which anchors the said shaft in the supports. The side walls of the housing are arranged to lie against the outer face of the rocker arm supports and thus when the fastening device is screwed down, thereby 45 fastening the housing to the bridge carried by these supports, the housing structure is properly positioned with respect to the rocker arm pivotally supported between the spaced rocker arm supports.

50 Figure 3 illustrates a modified form of fastening device wherein a bolt 22 is provided, which may be inserted through a perforation 23 in the bridge and the perforation 20 in the housing, a nut 24 screwed down 55 on the bolt to clamp the housing to the bridge, a cotter pin 25 then being inserted in the bolt to prevent the retraction of the nut 24.

55 Figures 5 to 8 inclusive illustrate further modified forms of construction wherein an arched bridge is utilized to compensate for the shorter supports 10 and 11, the rocker arm being positioned beneath the arched portion of the bridge, and the housing arranged to be fastened solely to the said arched portion. The use of rocker arm supports of

gine, the combination of a cylinder, valve smaller size, materially reduces the overall weight of the engine. With reference to Figure 5, it will be noted that a slightly modified form of fastening device is used, an externally threaded stud 26 being welded or otherwise secured to the arched bridge 13^a, and a nut 27, similar in construction to that illustrated in Figure 3, utilized for fastening down the housing structure.

70 With reference to Figure 6, it will be noted that a different form of arched bridge is used and the rocker arm shaft is fastened in the supports and prevented from endwise movement by the dowel 28 that engages within the annular groove 29 in the rocker arm shaft 12^a. If desired, this dowel 28 may be formed as an extension of one of the fastening devices 14, which secure the bridge structure 13^b to the rocker arm supports. In addition 75 Figure 6 illustrates another type of fastening device for fastening down the housing structure. In the structure herein illustrated, the cut-away portion 21 is eliminated and the housing is fitted flush against the outside face of each rocker arm support, the nut 30 being screwed down on the stud 31 carried by the bridge 13^b until the housing is firmly anchored in place. A split ring 32 is sprung 80 into the annular groove 32 carried by the nut 30 to lock the housing structure to the nut.

85 Figure 7 shows a bridge structure similar to that shown in Figure 6 and a fastening device similar to that shown in Figure 6 together with a housing structure similar to that shown in Figure 4.

90 It will be noted that with the structure as described above, that I have provided a separate housing for inclosing the valve mechanism, that may be very readily and quickly detached by removing the single removable fastening means which clamps the housing to the bridge. The single fastening means 95 firmly anchors the housing to the cylinder casting, and so cooperates with the rocker arm supports as to position the said housing with respect to the rocker arm pivotally supported between said supports.

100 The rocker arm housing is simple in construction and may be very economically manufactured as well as very quickly and economically assembled with the engine structure.

105 Although I have illustrated but one form 110 of my invention and have described in detail but a single application thereof, it will be apparent to those skilled in the art to which my invention pertains, that various modifications and changes may be made therein without departing from the spirit of my invention or from the scope of the appended claims.

115 What I claim as my invention is:

1. In an air cooled internal combustion en- 120

- operating mechanism therefor positioned substantially beyond the outer limits of said cylinder, a pair of spaced supports carried by said cylinder, a rocker arm pivotally supported between said supports, a bridge secured to said supports and spanning said rocker arm, and a rocker arm housing secured to said bridge.
2. In an air cooled internal combustion engine, the combination of a cylinder, a valve operating mechanism therefor positioned substantially beyond the outer limits of said cylinder, a pair of spaced supports carried by said cylinder, a rocker arm, means for pivotally securing the rocker arm to said supports, a bridge secured to said supports and spanning said rocker arm, and a separate rocker arm housing secured to said bridge and provided with means cooperating with 20 said supports for positioning the housing with respect to the rocker arm.
3. In an air cooled internal combustion engine, the combination of a cylinder, valve operating mechanism therefor positioned substantially beyond the outer limits of said cylinder, a pair of spaced supports carried by said cylinder, a rocker arm, means for pivotally securing the rocker arm to said supports, a bridge secured to said supports and spanning said rocker arm, and a rocker arm housing secured to said bridge and provided with side walls arranged to cooperatively engage said supports to position the housing with respect to the rocker arm.
4. In an air cooled internal combustion engine, the combination of a cylinder, valve operating mechanism therefor positioned substantially beyond the outer limits of said cylinder, a pair of spaced supports carried by said cylinder, a rocker arm, means for pivotally securing the rocker arm to said supports, a bridge secured to said supports and spanning said rocker arm, a rocker arm housing, means for securing the housing to the bridge, and means for positioning the housing with respect to the rocker arm housed therein.
5. In an air cooled internal combustion engine, the combination of a cylinder, valve operating mechanism therefor positioned substantially beyond the outer limits of said cylinder, a pair of spaced supports carried by said cylinder, a rocker arm pivotally supported between said supports, a bridge secured to said supports and spanning said rocker arm, a rocker arm housing, and a single removable fastening means for securing said housing to the bridge.
6. In an air cooled internal combustion engine, the combination of a cylinder, valve operating mechanism therefor positioned substantially beyond the outer limits of said cylinder, a pair of spaced supports carried by said cylinder, a rocker arm pivotally supported between said supports, an arched
- bridge secured to said supports and spanning said rocker arm, and a rocker arm housing secured to the arched bridge.
7. In an air cooled internal combustion engine, the combination of a cylinder, valve operating mechanism therefor positioned substantially beyond the outer limits of said cylinder, a pair of spaced supports carried by said cylinder, a rocker arm pivotally supported between said supports, a bridge structure secured to said supports and spanning said rocker arm, and a rocker arm housing secured solely to said bridge.
8. In an air cooled internal combustion engine, the combination of a cylinder casing, valve operating mechanism therefor including a rocker arm and positioned substantially beyond the outer limits of said cylinder, means for supporting the rocker arm with respect to the cylinder, a rocker arm housing, a single fastening means for removably securing said housing to the casing, and means including a depending portion carried by the housing and adapted for engagement with rocker arm supports for positioning said housing with respect to the casing and rocker arm.
9. In an air cooled internal combustion engine, the combination of a cylinder, a valve operating mechanism therefor positioned substantially beyond the outer limits of said cylinder, spaced rocker arm supports carried by the cylinder, a rocker arm pivotally supported therebetween, a bridge secured to said supports and provided with an externally threaded stud, a rocker arm housing provided with a perforation through which said stud is projected, and a nut adjustably secured with said stud to secure the housing to the bridge.
10. In an air cooled internal combustion engine, the combination of a cylinder, a valve operating mechanism therefor positioned substantially beyond the outer limits of said cylinder, spaced rocker arm supports carried by the cylinder, a rocker arm pivotally supported therebetween, a bridge secured to said supports and provided with an internally threaded hole, a rocker arm housing provided with a perforation, and a fastening device having an externally threaded shank arranged to be threaded through the perforation in the housing and screwed into the internally threaded hole in the bridge to secure the housing to said bridge.
11. In an air cooled internal combustion engine, the combination of a cylinder, a valve operating mechanism therefor positioned substantially beyond the outer limits of said cylinder, spaced rocker arm supports carried by the cylinder, a rocker arm pivotally supported therebetween, a bridge secured to said supports and spanning said rocker arm, a box-like sheet metal rocker arm housing for completely enclosing said valve control mech-

anism beyond the outer limits of the cylinder, and a single fastening means for removably securing said housing to said bridge structure.

12. In an air cooled internal combustion engine, the combination of a cylinder, valve operating mechanism therefor positioned substantially beyond the outer limits of said cylinder, a pair of spaced supports carried by said cylinder, a rocker arm, means for pivotally securing the rocker arm to said support, a bridge secured to said supports and spanning said rocker arm, and a rocker arm housing secured to said bridge and provided with side walls engaging the outer faces of said supports to position the housing with respect to the rocker arm.

13. In an air cooled internal combustion engine, the combination of a cylinder, valve operating mechanism therefor positioned substantially beyond the outer limits of said cylinder, a rocker arm, means carried by said cylinder for supporting the rocker arm, a rocker arm housing, a single fastening means for securing the housing to said cylinder, and pilot means for positioning said housing with respect to the rocker arm.

In testimony whereof I affix my signature.
